US00D820813S

(12) **United States Design Patent** (10) **Patent No.:** **US D820,813 S**
(45) **Date of Patent:** **** Jun. 19, 2018**

(54) **HEADSET WITH MICROPHONE**

(71) Applicant: **Logitech Europe S.A.**, Lausanne (CH)

(72) Inventors: **Douglas Paul Sharp**, San Francisco, CA (US); **Cormac O'Conaire**, Cabinteely (IE); **James Rennick**, Dublin (IE)

(73) Assignee: **LOGITECH EUROPE, S.A.**, Lausanne (CH)

(**) Term: **15 Years**

(21) Appl. No.: **29/585,676**

(22) Filed: **Nov. 28, 2016**

Related U.S. Application Data

(63) Continuation of application No. 29/533,975, filed on Jul. 23, 2015, now Pat. No. Des. 772,842.

(57) **CLAIM**

The ornamental design for a headset with microphone, as shown and described.

DESCRIPTION

FIG. 1 is a top front perspective view of a headset with microphone in an extended position showing our new design;

FIG. 2 is a bottom rear perspective view thereof;

FIG. 3 another top front perspective view thereof;

FIG. 4 is another bottom rear perspective view thereof;

FIG. 5 is a front elevational view thereof;

FIG. 6 is a right side elevational view thereof;

FIG. 7 is a rear elevational view thereof;

FIG. 8 is a left side elevational view thereof;

FIG. 9 is a top plan view thereof;

FIG. 10 is a bottom plan view thereof;

FIG. 11 is a top front perspective view of the headset with microphone in a retracted position;

FIG. 12 is a bottom rear perspective view thereof;

FIG. 13 another top front perspective view thereof;

FIG. 14 is another bottom rear perspective view thereof;

FIG. 15 is a front elevational view thereof;

FIG. 16 is a right side elevational view thereof;

FIG. 17 is a rear elevational view thereof;

FIG. 18 is a left side elevational view thereof;

FIG. 19 is a top plan view thereof; and,

FIG. 20 is a bottom plan view thereof.

The broken lines are directed to unclaimed surface features and are for illustrative purposes only; the broken lines form no part of the claimed design.
